UNITED STATES PATENT OFFICE.

GEORGE SCHUBEL, OF RIDGEWOOD, NEW YORK.

DIRECTORY.

1,364,527.

Specification of Letters Patent.

Patented Jan. 4, 1921.

Application filed April 5, 1920. Serial No. 371,248.

To all whom it may concern:

Be it known that I, GEORGE SCHUBEL, citizen of the United States, and resident of Ridgewood, in the county of Queens and 5 State of New York, have invented certain new and useful Improvements in Directories, of which the following is a specification.

This invention relates to directories, information books, and the like, and has for 10 its main object to provide a ready reference directory of information having a cover index which will at a glance indicate the section of the book in which the desired information is to be found.

Another object of the invention is to provide a combination of colors or shades on 15 the cover of the book, and to provide correspondingly colored or shaded sections within the book, each color or shade on the cover bearing a caption indicative of the kind of information to be found on the similarly-colored or shaded section within the book.

20 The above and other objects will become apparent in the description below, in which characters of reference refer to like-named parts in the drawings.

Referring briefly to the drawings, Figure 25 1 is a view of my directory showing the cover index thereof.

Fig. 2 is a view in end elevation of the directory, showing the arrangement of sections within the book.

30 Fig. 3 is a view of the directory when opened, partly in section, showing the arrangement of sections within the book.

Referring now in detail to the drawings, the numeral 1 represents the usual stiff or 35 flexible cover of the directory, and 2 the back thereof. The numeral 3 represents the sectional or loose-leaf binding means preferably used with my directory, and which is the subject of my co-pending application 40 for a United States Patent, bearing Serial No. 345,629, filed Dec. 17, 1919.

On the cover 1 of the book is arranged a ready reference index as shown, comprising 45 a central design bearing the title of the book, and radiating sectors emanating from said central design, each of said sectors bearing a caption, as shown. The said sectors may be variously shaded or colored; in the drawing, the sector 5 is red, 15 is green, 13 50 is orange, 11 is brown, 9 is blue, and 7 is yellow. Of course I do not desire to limit myself to any particular variety or arrangement of colors or shades, nor to the number of captions on the cover, nor to the same number of sections within the book. I have 60 provided white or uncolored sectors between each pair of neighboring colored sectors, as at 4, 6, 8, 10, 12, and 14, in order to the better offset the sectors which are colored.

The interior of the book is composed of 65 a number of separate sections, each in itself containing all the desired information about one subject, or a group of related subjects. The sections are severally releasably bound by the binding means 3, or by any other desirable binding means. The several sections in the book are colored corresponding to the colored sectors on the index, thus: the section 7^a, which is yellow, contains information about "churches;" the section 9^a, which 70 is blue, contains information about "hospitals;" 11^a, brown, about "libraries and schools;" 13^a, orange, about "officials;" 15^a, green, about "trolleys," or "surface cars;" and 5^a, red, about "banks and institutions." 80

In use, should one desire, for instance, to call a hospital, or to learn its address, or to gather any other information about it which may be contained in the directory, he will at a glance note that the caption "Hospitals" 85 lies in a blue ground, and he will quickly find the blue section 9^a within the book, in which he will then readily find the information about the particular hospital in which he is interested.

90 The directory is very practical and useful in cities, towns, communities, etc., in which it is important for people to be able to locate, either by telephone number or street address, such places as above-mentioned. Of course, the directory may contain any other 95 information as desired, arranged in any desired manner.

Thus it is apparent that I have provided a useful ready reference directory and index 100 therefor.

I claim:

A directory, book, or the like, comprising a cover, a plurality of sections contained within said cover, characteristic colors on 105 said sections, an index on said cover comprising a central portion bearing the title of the book, captions arranged in radial sectors on said cover surrounding said central portion, each of said sectors being 110 colored in correspondence with one of said sections.

GEORGE SCHUBEL.
